UNITED STATES PATENT OFFICE.

STEPHEN S. NEWTON, OF BINGHAMTON, NEW YORK.

BOTTLE-STOPPER.

SPECIFICATION forming part of Letters Patent No. 250,163, dated November 29, 1881.

Application filed February 26, 1878.

To all whom it may concern:

Be it known that I, STEPHEN S. NEWTON, of Binghamton, in the county of Broome and State of New York, have invented certain new and useful Improvements in Bottle-Stoppers; and I do hereby declare that the following is a full, clear, and exact description of the invention, which will enable others skilled in the art to which it appertains to make and use the same, reference being had to the accompanying drawing, and to the letters of reference marked thereon, which form a part of this specification.

The object of my invention is to provide a cheap, compact, and effective construction of bottle-stopper especially adapted for bottles used for perfumery, tooth-washes, and other toilet articles from which it is desirable to discharge the liquid in drops or fine jets.

Such devices have been usually so constructed that the caps or stoppers proper have been made detachable from the other part. More recently, however, caps or stoppers have been permanently attached, although capable of adjustment to allow discharge of the contents of the bottles; but the construction or means whereby such permanent attachment is effected have certain defects, which it is the object of my invention to remedy. To this end I construct my bottle-stopper as shown in the accompanying drawing, in which—

A represents the body of the bottle; B, a cork fitting tightly within the neck and provided with a central opening, in which is inserted a discharging-tube, E, preferably provided with an external screw-thread at its lower end.

D is a flange, projecting horizontally from the central part of the discharging-tube and covering the top of the cork and bottle-neck. C is a flange or skirt, depending from flange D in such manner as to inclose the neck of the bottle and hide the cork, thereby adding to the appearance of the bottle.

The extreme upper end of the discharging-tube is formed into a circular head, f^3 , the

contracted neck f of which is provided with a number of ports, f' , opening into the discharging-tube. The discharging-tube is expanded immediately below the ports, as at F, and screw-threaded at this point. G is a cap or cover, provided at its upper end with a port or opening, g , and is of such internal conformation as to form a valve-seat, which fits accurately the part f^3 of the discharging-tube. This cap is screw-tapped internally, so as to engage with the enlarged screw-threaded part F of the discharging-tube. After the cap G is screwed upon the discharging-tube its lower end is turned inwardly, (by spinning or otherwise,) so as to form a lip, g^3 , adapted to engage with the lower side or shoulder of the part F as the cap is screwed upwardly, and thus prevent the cap from being removed from the discharging-tube.

When preferred a washer or other packing, H, may be employed to prevent leakage between the lower part of the cap G and the discharging-tube. By turning the cap in one direction it is screwed down on the upper end or head, f^3 , of the discharging-tube, and thus prevents the discharge of the contents of the bottle, and by turning it in the other direction it is screwed up or out and opens the discharge-passage more or less to allow the escape of the contents of the bottle.

What I claim is—

The improved stopper formed of the screw-tapped cap G, having a port, g , and the inwardly-turned lip g^3 at its lower end, and the tube E, having a screw-threaded enlarged part, F, forming a circular shoulder, with which said lip engages when the cap is screwed out to open the discharge-orifice, substantially as set forth.

In testimony that I claim the foregoing as my own I affix my signature in presence of two witnesses.

STEPHEN S. NEWTON.
